BATTERY SERVICING

John J. Williams, Bridgeport, Conn.

Application April 18, 1944, Serial No. 531,676

3 Claims. (Cl. 29—246)

1

This invention relates to tools for use with storage batteries and the like, and more particularly to tools and methods for removing and cleaning battery terminals.

An object of the invention is to provide a means and method for removing and cleaning the terminal clamps of a storage battery whereby this may be done quickly, conveniently and thoroughly, without damage to the battery, and with but a minimum of skill and time being required on the part of the operator.

This is accomplished by the provision of an improved tool adapted to clasp a storage battery terminal clamp and be operated by a simple gentle movement to force the clamp from the battery post and obviating the hammering or tapping usually necessary for this operation. Preferably the tool is adapted to grip and support the battery clamp after its removal so that the operator may conveniently hold the latter firmly to clean the post-receiving aperture thereof.

In the form of the invention illustrated herein, as exemplary thereof, the tool comprises a pair of levers or handles, and jaws associated therewith adapted to clasp the underside of the battery terminal clamp, while a plunger which is operated by a cam-lever functions to force the battery post outwardly of the terminal clamp to loosen and remove the latter from the battery. The jaws of the tool are made to grip the terminal clamp so as to securely hold it after its removal, and the cam-operated plunger is hinged so it may be swung out of the way and permit a wire brush or other suitable cleaning implement to be passed through the post-receiving aperture of the terminal clamp to thoroughly clean the latter. The terminal clamp may then be quickly released from the tool by the operator merely releasing his grasp on the levers or handles so that the clamp may be reinstalled when ready.

The device and method as thus provided by the invention makes the comparatively difficult task of removing the terminal clamp easy and safe to do. In the servicing of automobiles, the battery is often neglected because of the difficulty of properly cleaning the terminals thereof. Through the use of the present improved tool and method, it is a comparatively simple matter to remove, clean and replace the battery terminals, and this operation can be done very quickly. This provides an incentive to the serviceman so that he can profitably service the battery of an automobile.

2

Other features and advantages will hereinafter appear.

In the accompanying drawings—

Figure 1 is a plan view of the tool of this invention, showing the cam-operated plunger means swung aside preparatory to clasping the tool over a battery terminal clamp.

Fig. 2 is a section taken on the line 2—2 of Figs. 1 and 3.

Fig. 3 is a fragmentary front elevation of the tool about to be closed over a battery terminal clamp, the clasping jaws being shown in section.

Fig. 4 is a vertical section of the tool showing the jaws embracing the battery terminal clamp, and the cam-operated plunger in position to separate the battery post and the terminal clamp.

Fig. 5 is a view similar to Fig. 4, but with the cam-lever and plunger in operated position and the terminal clamp loosened from the battery post.

Fig. 6 is a perspective view of a fragment of a battery showing a terminal clamp as carried on the terminal post, with the clamping bolt removed, preparatory to loosening and removal by the tool of this invention.

Fig. 7 is a perspective view showing the terminal clamp carried in the tool which is held in one hand of the operator while the other hand holds a wire brush in position to be inserted in and clean the post-receiving hole of the terminal clamp.

Referring to Figs. 1 and 2, the tool of the present invention comprises a pair of plier-like levers 10 and 11 pivotally connected intermediate their ends by a pin 12 and having elongate handle portions 13 and 14 respectively. The opposite end portions 15 and 16 of the levers 10 and 11 respectively, extend alongside each other, being comparatively flat and lying substantially in the same plane as shown. The portions 15 and 16 are bent at A so that they may be horizontal while the handles extend upwardly at an angle and thus avoid interference with adjacent objects.

According to the present invention, the portions 15 and 16 of the levers are provided respectively with flat jaws 17 and 18 which extend laterally of the direction of movement of said portions, the ends of the jaws having inwardly extending flanges or claws 19 and 20 respectively. Opposite the claws 19 and 20, the jaws 17 and 18 have a second set of flanges 21 and 22 which are secured to or form a continuation of the portions 15 and 16 of the lever.

As shown in Fig. 3, the jaws 17 and 18 are positioned and shaped to clasp between them a

battery terminal clamp 23 with the flanges 19 and 20 of the jaws being positioned to engage the underside of the clamp when the levers 15 and 16 are brought together by hand pressure thereon.

The tool of this invention also includes means for engaging the end of the battery post 24 on which the terminal clamp 23 is carried, and for conveniently applying pressure to the end relatively to the clamp to loosen the latter from its grip on the post, so that it may be easily lifted from the battery, all without having to resort to hammering or other similar expedients which are injurious to the battery case and plates. This means is movably mounted so that it may be placed across the jaws 17 and 18 to accomplish this purpose, and after removal of the clamp 23 from the battery post may be moved to one side to permit insertion of a wire brush or other suitable device in the post-receiving aperture of the clamp to clean same.

Accordingly, as shown in Figs. 3 and 4, the jaw 17 has attached thereto, as by welding or other suitable means, a plate 25 on which is hinged a plate 26 of a length sufficient to extend across the open end of the jaws over an abutment plate 27 mounted on the jaw 18 to bridge the space between the jaws when they are in terminal-engaging position. The abutment plate 27 carries a pivotally mounted screw 28 adapted to be received in a slot 29 in the bridging plate 26. The screw 28 is provided with a winged nut 30 by means of which the bridging plate 26 is securely clamped to the abutment plate 27 when the jaws 17 and 18 are embracing the battery terminal clamp 23 as shown in Fig. 4.

The bridging plate 26 has a central threaded aperture which receives an externally threaded sleeve 31 adapted to extend between the jaws 17 and 18 and past the flanges 21 and 22 thereof, which latter are cut away at 32 and 33 respectively for clearance. By rotating the sleeve 31 the end 34 thereof may be moved into close proximity to the end of the battery post 24. The other end 35 of the sleeve 31 is bifurcated and apertured for a pin 36 upon which a hand lever 37 pivots, the pivoting end 38 of the lever extending between the forks of the end 35 of the sleeve.

For applying force to the battery post 24, a plunger 39 having a head 40 is slidably carried in the sleeve 31, the head being flattened at opposite sides so that it may be received between the forks of the bifurcated end 35 of the sleeve. In order to operate the plunger 39 to engage the battery post 24 and apply force to same, the pivoting end of the hand lever is provided with a cam surface 38'. When the lever is in the position shown in Fig. 4 and the tool is placed on the terminal clamp and post, the plunger 39 will be pushed up to retracted position in the sleeve 31. When the hand lever is moved to the position shown in Fig. 5, the camming surface 38' thereof forces the plunger 39 downward to a position where the end 41 thereof projects beyond the end 34 of the sleeve 31.

In operating the tool of this invention for removing the terminal clamp 23 from the battery post 24, the tool is first placed in the position shown in Fig. 3, after which the handle portions 13 and 14 are moved towards each other and held. This causes the jaws 17 and 18 to engage and hold the terminal clamp 23. The hand lever 37 is now grasped, and the bridging plate 26 swung into position across the jaws 17 and 18 as shown in Fig. 4, whereupon the screw 28 and

winged nut 30 are operated to tightly clamp the plate against the abutment plate 27. This holds the jaws 17 and 18 firmly against moving outwardly away from the terminal clamp 23. The lever 37 is now held to extend laterally of the sleeve 31, and rotated about the axis of said sleeve in a clockwise direction to advance the latter into the bridging plate 26 so that the end 34 of the sleeve and the plunger 39 carried thereby approach closely the end of the battery post 24. Then the lever 37 is swung up about the pivot pin 36 as indicated by the arrow in Fig. 4, causing the cam 38' thereon to depress the plunger 39 as shown in Fig. 5, thereby partially pulling the terminal clamp 23 from the battery post 24. The terminal is thus sufficiently loosened so that it may be readily lifted from the battery and held by the tool.

It will be noted that the force applied by the operator to loosen the terminal clamp from the post is in an upward direction, that is to say, away from the battery and not downwardly on the post. There is, therefore, no danger of the post being pushed through the sealing compound or battery top through which the post extends.

After the tool is used for pulling and removing the battery terminal clamp, it still grips the latter and thus may be used to enable the operator to firmly hold the clamp for cleaning the post-receiving aperture thereof. Thus the operations of removing the terminal clamp and cleaning same are combined and greatly facilitated by the use of the tool of this invention so that time and labor are saved.

In preparation for this cleaning, after removal of the clamp from the post as just described, the lever 37 is grasped and operated to unscrew the sleeve 31 an extent from the bridging plate, and the winged nut 30 is loosened to permit the bridging plate 26 and sleeve and plunger carried thereby to be swung to an out-of-the-way position as shown in Fig. 7. A wire brush 42 may now be passed back and forth through the aperture 23a of the terminal clamp to thoroughly clean same, whereupon when the operator relinquishes his grasp of the hand portions 13 and 14 of the levers, the clamp is released from the tool in readiness for being reinstalled.

Variations and modifications may be made within the scope of this invention and portions of the improvements may be used without others.

I claim:

1. A tool for removing a surrounding member from a post comprising a pair of levers pivotally connected together; jaws on the levers so constructed to engage the sides of the surrounding member with the jaws swinging in a plane at right angles to the post; a bridging member lying in a plane parallel to said first plane, connected to one jaw, extending across the opening of the jaws and across the top of the post and connected to the other jaw; a post-engaging member movably mounted on said bridging member for movement axially of the post and the opening of said jaws; and means for moving said post-engaging member relative to said levers to force the post from the surrounding member.

2. A tool for removing a surrounding member from a post comprising a pair of levers pivotally connected together; jaws on the levers so constructed to engage the sides of the surrounding member with the jaws swinging in a plane at right angles to the post; a bridging member lying in a plane parallel to said first plane, said member being pivotally connected to one jaw, extend-

ing across the opening of the jaws and across the top of the post and detachably connected to the other jaw; a post-engaging member movably mounted on said bridging member for movement axially of the post and the opening of said jaws; and means for moving said post-engaging member relative to said levers to force the post from the surrounding member, the bridging member being movable about the pivotal connection from said bridging position whereby the post receiving aperture is unobstructed and may be cleaned after the post is removed and while the surrounding member is held in said jaws.

3. A tool for removing a surrounding member from a post comprising a pair of levers pivotally connected together, jaws on the levers so constructed to engage the sides of the surrounding member with the jaws swinging in a plane at

right angles to the post, the jaws having portions along one side and extending under the surrounding member; a bridging member lying in a plane parallel to said first plane, connected to one jaw, extending across the opening of the jaws and across the top of the post and connected to the other jaw to hold said jaws against lateral separation; a post-engaging member movably mounted on said bridging member for movement axially of the post and the opening of said jaws; and means for applying pressure to the post-engaging member to force the member toward the post and by the same operation forcing the jaws and portions extending under the surrounding member in the opposite direction to cause the post to move out of the surrounding member.

JOHN J. WILLIAMS.
